UNITED STATES PATENT OFFICE

152,244

DESIGN FOR A JACKET

Simon Etkin, New York, N. Y.

Application July 13, 1948, Serial No. 147,531

Term of patent 3½ years

(Cl. D3—4)

To all whom it may concern:

Be it known that I, Simon Etkin, a citizen of the United States, residing in the city of New York, in the county of New York and State of New York, have invented a new, original, and ornamental Design for a Jacket, of which the following is a specification, reference being had to the accompanying drawing, forming part thereof.

Fig. 1 is the front view of a jacket, showing my design.

Fig. 2 is the rear view of the jacket shown in Fig. 1, and

Fig. 3 is a side of the jacket shown in Figs. 1 and 2 illustrating the loose and stitched portions of the collar and yoke trim.

I claim:

The ornamental design for a jacket, substantially as shown.

SIMON ETKIN.
